UNITED STATES PATENT OFFICE.

GEORGE B. CAMPBELL, OF WHITE BEAR, MINNESOTA, ASSIGNOR OF ONE-HALF TO
SAMUEL J. JOY, OF ST. PAUL, MINNESOTA.

ELECTRIC BATH-CABINET.

1,095,957.

Specification of Letters Patent.

Patented May 5, 1914.

Application filed February 19, 1914. Serial No. 819,731.

To all whom it may concern:

Be it known that I, GEORGE B. CAMPBELL, a citizen of the United States, residing at White Bear, in the county of Ramsey and 5 State of Minnesota, have invented new and useful Improvements in Electric Bath-Cabinets, of which the following is a specification.

My invention relates to improvements in 10 electric bath cabinets. Access to devices of this nature, as heretofore constructed, is more or less difficult and the patient, after the bath, is required to move from within the cabinet to a massaging or cooling table 15 outside the cabinet.

It is the object of my present invention to provide a simple, compact and easily accessible bath cabinet having a housing, and a movable table therefor, the latter serving as 20 a support for the body of a patient at full length and as a carriage to move the patient into and out of the housing, said housing being adapted to receive the patient while reclining upon the table and to inclose his 25 body while his head is exposed to the outer air.

In the drawings, Figure 1 is a perspective view showing the cabinet closed; Fig. 2 is a vertical, central, sectional view of the same; 30 Fig. 3 is a perspective view of the cabinet showing the table and cabinet door in positions to receive a patient and Fig. 4 is an end elevation in detail illustrating the mounting of the cabinet door and the spring 35 arrangement at one end thereof.

Referring to the drawings, I have used the reference numeral 10 to indicate the housing. One end frame of said housing is an angle iron 11 bent in the form of an inverted U and the other end frame consists of angle irons 12 and 13, the former being bent in the shape of an inverted L and the latter forming an upright post. These frames are reinforced by transverse bars 14 and are 40 joined by longitudinal bars 15 and 16. The end 17, back 18 and top 19 of the housing are solid rectangular sheets of metal or the like secured in any suitable manner to the frame. The end 20 is similar to the end 17, 45 excepting that the upper forward portion thereof is cut away as will be more fully hereinafter described. The panel 22 of sheet metal, or the like, is secured to the bars 16 on the front side of the cabinet. 50 The table 25 provides a support upon

which a patient may lie, and a carriage for moving said patient into and out of the housing 10. This table comprises side and end rails 29 and 30, legs 27 with casters 28 thereon, a removable concave top 26 formed with parallel slats 31, joined by cleats 32, and a head rest 33 secured to and extending beyond one of the end rails 30. The handles 34 on the side rail 29 furnish means by which said table may be moved. Openings 60 24, between the panel 22 and the end frames 11 and 13, receive the forward legs 27 of the table and the opening 21, formed in the end 20, furnishes a passage through which the head rest 33 and the neck of the patient 65 may move when the table is placed within the cabinet. 70

The cabinet is provided with a swinging door 35, composed of a front panel 36, formed with flanges 40 and 41, and an end panel 37, formed with a flange 42. When the housing is shut, the fixed panel 22, the table 25 and the panel 36, of the swinging door 35, inclose the front of the cabinet. The end panel 37 of said swinging door is 75 formed with an opening 45 corresponding with a contiguous opening 44 in the end wall 20 of the cabinet, which, when the door is in closed position, form an aperture through which the rest 33 and the head of the patient 80 protrude when said door is closed. The front panel 36 of said door 35 is provided with an arm 38 and said arm and the end panel 37 are attached by pivots 39 to the end frames of the cabinet and swing thereon 85 from closed position, as shown in Fig. 1, to open position, as illustrated in Fig. 3. The flanges 40 and 41 on the door panel 36 and the flange 42 on the door panel 37 overlap the end and top of the cabinet to form tight 90 joints between said door and cabinet. Handles 43, fixed to said door panel 36, are employed to open and close the door 35. 95

The weight of the door 35 is counterbalanced by the spring 46, which is attached at 100 one end to an extension 38^a on the arm 38 and secured at its other end to the housing beneath the pivot 39.

Incandescent heat lamps 47, connected as 105 desired with a suitable source of current, are mounted upon the longitudinal bars 15 and 16, above and below the table top, said lamps being controlled in any suitable manner, such as the switch 48 illustrated in Fig. 3. 110

A window 49 may be arranged in the end 20 of the cabinet and a thermometer 50 located adjacent to the inner side of said window for the inspection of patient and 5 attendant.

The drip pan 51, suspended by hooks 52 beneath the top 26, is carried by the table and clears the panel 22, as said table is moved into and out of the housing.

10 In use, the table 25 is first drawn out with the door 35 raised as shown in Fig. 3. The patient lies at full length upon the table top 26^a with his head upon the rest 33. Said table is then pushed into the housing, 15 the door 35 lowered and the switch 48 turned to light the lamps 47. The body of the patient is subjected to the heat from the lamps and to the light rays, which pass directly therefrom and are reflected from 20 the walls of the cabinet while his head is in the outer air and may be reached, if desired, to permit cold applications or the like. After sufficient exposure to the heat within the cabinet, the lamps are extinguished, the door raised and the table withdrawn to present the patient in convenient 25 position for immediate treatment.

Having described my invention, what I claim as new and desire to protect by Letters Patent, is:

30 1. In a cabinet, the combination of a housing and an operating table slidable therein, said table being provided with a head rest adapted to extend through an aperture in 35 the end of said cabinet and a closure for the front of said cabinet formed by a pivoted door and one side of said table.

40 2. In a cabinet, a housing having sides, ends and a top, one of said sides and ends being each formed with an opening therein, a table slidable into and out of the housing through the opening in said side, a head rest on said table adapted to pass through 45 the opening in the end and a door for said openings.

45 3. In a cabinet, a housing having sides, ends and a top, one of said sides and ends being each formed with an opening therein, a table slidable into and out of the housing 50 through the opening in said side, a head rest on the table adapted to pass through the opening in the end and a door for said openings, said door and end being formed with contiguous marginal openings adapted 55 to form an aperture to receive said head rest and the neck of the patient when said door is closed.

4. In a cabinet, a housing having sides,

ends and a top, one of said sides and ends being each formed with an opening therein, 60 a table slidable into and out of the housing through the opening in said side, a head rest on the table adapted to pass through the opening in said end and a door for said 65 openings comprising a side and end panel, and an arm on the side panel, said arm and end panel being pivoted upon the ends of the housing to permit the door to swing upwardly and rest upon said top and swing downwardly to close said openings. 70

5. In a cabinet, a housing having sides, ends and a top, one of said sides and ends being each formed with an opening therein, a table slidable into and out of the housing through the opening in said side, a head 75 rest on the table adapted to pass through the opening in said end, a door for said openings, comprising a side and end panel, and an arm on the side panel, said arm and end panel being pivoted upon the ends 80 of the housing to permit the door to swing upwardly and rest upon said top and swing downwardly to close said openings, and a spring attached at one end to said door and at its other end to said housing to counter- 85 balance the former.

6. In a cabinet, the combination of a housing and an operating table slidable therein, a closure for the front of said cabinet comprising one side of said table and a door 90 pivoted above the table, and a head rest, carried by said table, adapted to slide beneath said door when open and to protrude through the end of the cabinet when the door is closed. 95

7. In a cabinet, a housing having sides, ends and a top, one of said sides and ends being each formed with an opening therein, a table slidable into and out of the housing through the opening in said side and forming 100 a partial closure for said opening, a head rest on the table, adapted to pass through the opening in said end and a door for said openings, said door and end having adjacent portions thereof cut away to form 105 an aperture to receive said head rest and the neck of the patient when said door is closed.

In testimony whereof, I have signed my name to this specification in the presence of 110 two subscribing witnesses.

GEORGE B. CAMPBELL.
